UNITED STATES PATENT OFFICE.

LEO L. LUX, OF GREELEY, COLORADO.

RETAINING ATTACHMENT FOR OPERATING TABLES.

Application filed April 19, 1921. Serial No. 462,731.

To all whom it may concern:

Be it known that I, LEO L. LUX, a citizen of the United States, residing at the city of Greeley, and county of Weld and State of Colorado, have invented certain new and useful Improvements in Retaining Attachments for Operating Tables; and I do declare the following to be a full, clear, and exact description of the invention, such as will enable others skilled in the art to which it appertains to make and use the same, reference being had to the accompanying drawings, and to the characters of reference marked thereon, which form a part of this specification.

The object of this invention is to provide a simple device which may be quickly attached to operating tables to assist in holding the patient.

Briefly, the invention comprises a clamp adapted to be secured to the table and having a positively operating strap retainer for holding one end of the strap. Two forms of the clamp are used. One form has one end of the strap permanently secured thereto on the inner face of one of the jaws where it may serve as a cushion for the clamp, said clamp also carrying on its outer face a swinging retainer to engage the other end of the strap. The other form of the clamp is to be used in connection with the first form where it is impossible to engage the free end of the strap with said first clamp. In this second form, the clamp has a swinging retainer disposed in an opposite direction from the retainer of the other form.

In the drawings:

Fig. 1 is an elevation showing one form of clamp as indicated by the line 1—1 of Fig. 2;

Fig. 2 is a face view thereof taken from the line 2—2 of Fig. 1;

Fig. 3 is a vertical section through the other form of clamp;

Fig. 4 is a view showing one use of the device where both forms of clamp are required;

Fig. 5 is a view showing the use where only one clamp is employed;

Fig. 6 is a face view of the form of clamp of Fig. 3; and

Fig. 7 is a detail taken from the line 7 of Fig. 4.

The clamp comprises a body member 10 having a jaw 12 which receives the screw 14

carrying on its inner end an engaging head 15 swiveled on the screw 14 by means of fingers 16 which enter a groove 18 in the screw, the outer end of the screw being provided with a thumb piece 20. The body 10 carries a second jaw 22 parallel with the jaw 12, said jaw 22 having a pair of offset ears 25 carrying between them a bar 26. Directly above said ears 25 is another pair of ears 28 on said jaw 22 which carry a transverse rod or bar 30. In the form of Figs. 1 and 2 a strap retaining plate 32 is pivoted upon the bar 26 by means of an eye 34, the free end of the plate being toothed, as shown, to insure firm engagement with the strap S. 70 The inner face of the jaw 22 is provided with a cushioning pad 35 to engage directly with the table T to avoid marring the outer surface thereof. The clamping head 15 and screw 14 are positioned under the table and 75 on the inner side of that portion to which the clamp is secured.

In the form of clamp shown in Figs. 3, 5 and 6, the strap retaining jaw 36 is pivoted to the upper bar 30 by means of an eye 38, 80 its lower end being toothed, as shown, to positively engage the strap S, the plate 36 co-operating with the bar 26 in the same manner which the plate 32 co-operates with the bar 30. With this second form of clamp 85 the strap S is permanently secured, as by means of a rivet 40, to the inner face of the jaw 22 so that the fixed end of said strap serves as a cushion in place of the pad 35 of Fig. 1. With this form the strap S may 90 be passed upward and over the table and thence under the table and over the rod 26 against which it is secured by the plate 36.

However, where it is not possible to pass the strap around the table in this manner, 95 the other form of clamp must also be employed. Such use is illustrated in Figs. 4 and 7. Here the second form of clamp is secured to the table as before, the strap being passed around the patient as indicated 100 in Fig. 4 and then returned to the side of the table at a spaced point. At this point the first form of clamp, as shown in Figs. 1 and 2 is used, the strap being brought downward behind the bar 30 and secured 105 thereagainst by the plate 32.

I claim:

1. A retainer comprising a pair of opposed jaws, means on one jaw to clamp the device on a table, and means on the outer 110

side of the other jaw to clamp and hold a strap.

2. A retainer comprising a pair of opposed jaws, means on one jaw to clamp a support held between the jaws, and a swinging strap retaining plate on the outer face of the other jaw.

3. A retainer comprising a pair of opposed jaws having means to clamp the device on a support, a pair of bars on the outer face of one jaw, and a plate mounted on one

bar to engage and hold a strap against the other bar.

4. In combination, a clamp adapted to be secured to a table, a strap secured to said clamp, a second clamp adapted to be secured to the table, a pair of bars mounted on said second clamp, and a plate mounted on one bar to engage and hold the strap against the other bar.

In testimony whereof I affix my signature.

LEO L. LUX.
